ELECTRICAL CORD-REEL

Bernard J. Tamarin, Philadelphia, Pa., assignor to
Vacuum Cleaner Corporation of America, Philadelphia, Pa.

Filed Apr. 6, 1972, Ser. No. 241,883

Term of patent 14 years

Int. Cl. D8—08

U.S. Cl. D8—220

FIG. 1 is a side elevation of an electrical cord-reel according to this invention, showing the right side thereof.

FIG. 2 is a front elevation of the cord-reel, taken at II—II on FIG. 1.

FIG. 3 is a side elevation of the cord-reel taken at III—III on FIG. 2, showing the left face thereof.

FIG. 4 is a bottom plan of the cord-reel, taken at IV—IV on FIG. 1.

I claim:

The ornamental design for an electrical cord-reel, substantially as shown.
